SEAM PROTECTING MEANS FOR CLOTH SHEARS

Charles G. Richardson, Springfield, Vt., assignor to Parks & Woolson Machine Company, Springfield, Vt., a corporation of Vermont

Application December 15, 1931, Serial No. 581,151

12 Claims. (Cl. 26—17)

This invention relates to cloth shearing machines and particularly to the type of shearing machines adapted to cropping or clipping a face of pieces of cloth, whose ends are sewed together transversely of the cloth, so that any number of pieces may be run through the machine for cropping as many times as may be desired without rethreading each piece of cloth through the machine after it has undergone a clipping operation.

As is well known to those skilled in the art, shearing machines of this type have usually been built with a transverse cloth supporting member, termed a cloth rest, for presenting the cloth to the action of a shearing couple embracing a revolving or rotary fly blade and a fixed ledger blade arranged on a plane substantially tangential to the periphery of the fly blade to form the stationary element of the shearing couple, both of these cutter members or elements being mounted in the same pivotal frame. Means have been employed heretofore for raising the cutter head or supporting frame away from the cloth rest to allow the ends of the sewings or transverse seams to pass by the shearing line without being severed or damaged by the cutters. Means have also been provided, as shown in my former Patent No. 1,372,978 dated March 29, 1921, for automatically dropping the cloth rest to allow the seamed ends to pass the shearing line without injury. It has also been proposed to provide a protective means, embracing a transverse bar mounted on a pivotal axis some distance above or below the cutters, to depress the cloth into a transverse gap formed in the cloth supporting rest, but such proposed arrangements have not been free from trouble since of necessity the pivoted protective member or plate must pass in close proximity to the periphery of the fly blade, and consequently there was danger that the fly blade should receive niches in its cutting edges, which of course is extremely objectionable.

As the cloth rest is preferably made of rather heavy construction and at the same time should be moved quickly to and from operative relation to the cutters, the use of a drop cloth rest involves a considerable amount of vibration due to the jar and shock attendant upon the rapid movement of this element. The depression of the cloth into the gap of the cloth rest also is not desirable, since it necessarily imposes an additional tension on the cloth travelling rapidly across it, which it is desirable to eliminate.

It is the object of the present invention to

overcome these and other difficulties and the invention consists, generally speaking, in combining with the shearing elements a protective arcuate hood that is pivoted coaxially with the rotary fly blade to swing close to its periphery toward and away from the edge of the ledger blade, while at the same time providing for a simultaneous movement of the cloth rest to a very limited extent, that is, just enough to allow the sewings to pass between the rear flange or lip of the cloth rest and the ledger blade, but without involving sufficient movement to require rapid action in either direction. The concentric mounting of the protective hood eliminates the danger of injury to either blade, since provision is made for limiting the pivotal movement to avoid contact between the advance edge of the protective hood and the edge of the ledger blade and at the same time there is no depressing of the cloth into the gap rest and only a very small degree of movement of the cloth rest away from normal active position. These and other features of the invention will be particularly described in the following specification and will be defined in the claims hereto annexed.

In the drawing I have illustrated a simple and convenient form of construction and arrangement embodying the principles of this invention, in which

Fig. 1 is an end elevation showing a portion of the cutter head carrying the rotary fly blade and its relatively stationary coacting ledger blade in conjunction with a drop cloth rest and seam actuated control mechanism, the guard member being held out of active or operative position.

Fig. 2 is a similar elevation illustrating the position of the different parts of the mechanism in position to allow the seam to pass the shearing line without injury.

Fig. 3 is a plan view, partly in section, showing one end bearing of the fly blade and seam protector.

In the accompanying drawing I have shown only so much of the well known shear construction as is necessary to understand the construction and operation of the present invention, the various guides, framework, and other well known parts of the machine not especially concerned with this invention being omitted.

A transverse rock shaft 1 supports the transverse pivotal cloth rest 2, which is provided, as shown in my aforesaid patent, with spaced transverse upwardly projecting ribs or lips 2^a forming an intermediate transverse gap over which the

cloth A travels as it is presented to the shearing elements.

The shearing elements comprise the usual rotary fly blade 4 and the tangentially disposed 5 relatively fixed ledger blade 5, both mounted in a single frame or head 3, so that the cutters may be lifted back to facilitate drawing the sewed together pieces of cloth through the machine preparatory to cropping one or both faces thereof.

10 As shown in detail in Fig. 3, the cutter head 3 is provided with a bushing bearing member 3^a, which receives the end of the fly blade shaft and projects through the outside of the frame to form a stub shaft or sleeve for supporting the pivotal 15 side arms 6, whose outer end edges are concentric with the axis of the shear blade and carry an arcuate plate or shield 8 which forms an arc of a cylinder so as to lie in concentric relation to the periphery of the shear, whatever the position 20 of adjustment of the seam protector may be. The side arms of the seam protector element are continued to form extensions 7 positioned to engage adjustable stop screws 9 mounted in lugs 10 on the outside of each side of the cutter head so 25 as to limit the movement of the seam protector toward the forward edge of the ledger blade 5. The weight of this protective shield is sufficient to cause its movement by gravity to a position 30 between the lower portion of the fly blade and the underneath cloth. The means illustrated in the present form of the invention for moving and maintaining the seam protector out of protective position, in order to allow the face of the cloth 35 to be presented to the shearing line, comprises a pivotal arm 20 mounted on each end of the cloth rest and provided with an arcuate transverse pin-receiving slot for engaging a stop member or pin 22 to limit the pivotal movement of the arm. The arm 20 is provided with a rearward extension 20^a forming a counterbalance 40 weight in order to maintain the upper end 21 of the arm in vertical registry with the overhead guard pin 6^a when the rest is shifted from one position to another. The upper end of this arm 45 20 is preferably arcuate or sector shaped, being struck on a radius from the pivotal center of the arm so that any to and fro movement of the arm does not affect the position of the thrust pin 6^a which engages the arcuate upper end of the arm when the cloth rest is in raised or active 50 position.

The means provided for positioning the cloth rest comprises a pivoted lever or latch 30 provided with a short concentric arcuate face 30^a, 55 which supports the rest in operative relation to the cutters, when the latch is in vertical position, by its engagement with a thrust member comprising a pin or lug 25 projecting from the end of the cloth rest. The peripheral surface of this 60 cam latch, as shown at 30^b, recedes toward the center so that when the cam is rotated in a counterclockwise direction the rest is permitted to drop a short distance from its normal operative position, as shown in Fig. 2. This leaves a sufficient 65 gap between the rear lip 2^a of the cloth rest and the overhanging ledger blade 5 to allow the seam to pass through without difficulty and at the same time the movement is so slight as to eliminate the jar and shock incident to the 70 dropping of cloth rests in previous machines of this type and also eliminates any sudden or abrupt change of tension on the cloth passing over the rest. This slight dropping of the cloth rest is sufficient to permit the seam protector 75 to drop to active position, since the supporting

arm 20 drops with the cloth rest allowing ample movement of the stop member or pin 6^a downward until the stop arm 7 forms contact with the stop screw 9. One advantage of this arrangement is that it in no way interferes with the raising of the cutter head when it is desired to draw through the machine a new supply of cloth. The slight pivotal movement allowed the arm 20 permits it to remain in vertical position, either when the cloth rest is dropped or when the cutter head is raised.

80 While it is obvious that the cloth rest rock shaft 1 may be actuated by the hand lever commonly used with this type of cloth rest, it is also clear that any suitable seam controlled mechanism may be used to cause simultaneous actuation of the cloth rest and of the seam protector.

90 In this instance, I have shown precisely the same mechanism for automatically causing simultaneous dropping of the cloth rest and of the seam protector as that shown in my former Patent No. 1,372,978. Briefly described, this mechanism comprises a pivotal arm or frame 11 having a yielding seam-engaging member 11^a at its outer end and secured to a rock shaft 12 on which is 100 fixed an arm 13, which swings in a clockwise direction when the outer end of the arm 11 is raised by engagement with the seam. On a transverse shaft 14 is secured a continuously revolving ratchet wheel 15, whose toothed periphery 105 revolves by the toe of an angular pawl 16 that is normally under the tension of a torsion spring 17 which tends to rotate it in a counterclockwise direction. This pawl is normally kept out of engagement with the ratchet wheel by means of a 110 pivotal latch 18 formed with a hook member that overhangs a stop pin 16^a on the pawl. The latch 18 like pawl 16 is carried on a lever 19 that is loosely mounted on the rock shaft 14 and the latch 18 has a projecting portion adapted to be 115 engaged by the arm 13 when the seam rocks the arm, so that the hook latch 18 is disengaged from the pawl stop pin 16^a allowing the pawl to move into engagement with the ratchet wheel. As the pawl is also carried by the arm 19, this engagement rocks the arm 19 in a clockwise direction 120 until the pawl 16, by its engagement with the fixed stop member 26, is forced relatively downward until it pushes the stop pin 16^a beneath the hook portion of the latch 18, thereby 125 releasing the pawl and allowing the rock arm 19 to drop back by gravity to normal position. The link 27 connects lever 19 with latch 30.

130 It will therefore be seen that the cloth rest needs but a very slight movement from normal position to allow the seam to pass through, since the seam ends are guarded against being cut by means of the protector, which is then in active protecting position and yet the objections to the dropping of the cloth rest, as heretofore practiced, are entirely eliminated. Furthermore, the 135 seam protector, having its movement concentric with the periphery of the fly blade, can be dimensioned to be spaced only slightly from the fly blade without danger of nicking its edges 140 and is also insured against contact with the edge of the ledger blade. The stop screw 9 permits a setting that will leave the gap between the adjacent edges of the ledger blade and of the seam 145 protector as narrow as may be desired. All this is accomplished without interfering in the least with the raising of the cutter head.

150 The above described seam controller means for dropping the cloth rest is practically identical with that described in my aforesaid patent,

but no provision was made in the disclosure of that patent for automatically restoring the cloth rest to its operative position and the present invention embraces the further improvement of 5 effecting the restoration of the cloth rest to operative position after the seam or sewing has passed by the cloth rest.

To lessen somewhat the unbalanced weight of the cloth rest 2, I provide a rearward extension 10 thereof comprising the arm 35 with the adjustable counterbalance weight 36, this counterbalance arm 35 being provided with an adjustable stop screw 37 mounted in a fixed part of the frame to prevent the cloth rest when moving upward to 15 normal position from moving against the shear blades.

Furthermore, the lower end of the latch or cam lever 30 is extended downward a short distance and there is pivotally connected to such 20 lower end a piston rod 38 to whose forward end is secured a piston 39 working in an air cylinder 40 closed at its forward end, except for a small vent controlled by an adjustable needle valve or screw 41. A helical compression spring 42 interposed between the piston head and the rear end 25 head of the pivotal air cylinder 40 normally acts to restore the cam lever 30 to vertical position for supporting the cloth rest in its normal operative position after the seam has passed by. The 30 cam surface 30^b, on which the supporting pin 25 of the cloth rest is engaged, acts under the pull of this spring, when the pawl 16 is released from the ratchet wheel 15, to lift the cloth rest to normal position, its work being lightened by the 35 partial counterbalancing effect of the weight 36.

As it may be desired to change the position of the stop that releases the pawl 16 from the ratchet wheel, I have provided the stop arm 26 with an adjustable stop screw 28 in order to vary 40 the length of the arc of travel before the pawl is disengaged. When the pawl is disengaged the spring 42 acts to restore the cam arm 30 to raised position, but such action is retarded to give ample time for the seam to clear the cloth rest by 45 means of the compressed air resistance in the forward end of the cylinder 40, which acts as a vented dash pot to give the desired retarding effect according to the adjustment of the vent-controlling screw 41.

50 It will be observed that the seam-protecting guard is freely movable about its pivotal axis concentric with the fly blade within the limits permitted by its lifting member 20 and the stop member 10, so that normally of its own weight 55 it rests upon the supporting actuating link 20 when the cloth rest is in active position, but the arrangement also permits the guard to be swung upward over its pivotal center when it is desired to thread the cloth through the machine between 60 the shearing elements. Furthermore, in its normal inactive position the seam guard permits the operator at the front of the machine to have unobstructed vision of all portions of the cloth up to the shearing line and in advance thereof, whereas 65 in previous proposed constructions the guard obscures the vision of the operator in front of the shearing line.

What I claim is:

70 1. In a cloth shearing machine the combination with a cloth supporting rest, of a cutter head embracing a coacting fly blade and ledger blade, a seam-protecting guard pivotally mounted for movement concentric about the axial center of the fly blade to and from the ledger blade to prevent contact of the seam with the ledger blade.

2. In a cloth shearing machine the combination with a cloth supporting rest, of a cutter head embracing a coacting fly blade and ledger blade, a seam-protecting guard pivotally mounted on the cutter head in coaxial relation with the fly blade to permit concentric movement about the periphery of the fly blade toward the ledger blade and also to prevent relative displacement between the guard and the peripheral path of the fly blade. 80

3. In a cloth shearing machine the combination with a cloth supporting rest, of a cutter head embracing a coacting fly blade and ledger blade, a seam-protecting guard pivotally mounted on the cutter head in coaxial relation with the fly blade to permit concentric movement about the periphery of the fly blade toward the ledger blade and also to prevent relative displacement between the guard and the peripheral path of the fly blade, and means for releasably maintaining the protector in raised position when the cutter head is 90 in its operative relation to the cloth rest. 95

4. In a cloth shearing machine the combination with a pivotal cutter head carrying a coacting fly blade and ledger blade, a pivotal cloth rest for supporting the cloth travelling over it in 100 position to be sheared by said blades, said rest being movable away from the shearing line as the seam approaches it, and a seam-protecting guard movable to position between the fly blade and the cloth rest without engaging the face of the cloth 105 when the rest is moved to inactive position.

5. A seam-protecting guard for a cloth shearing machine embracing an arcuate plate partly surrounding the fly blade of the shearing machine and movable in a path concentric with the fly 110 blade periphery, and adjustable means for limiting the movement of said guard to seam-protecting position.

6. A seam-protecting guard plate for a cloth shearing machine embracing a guard member 115 extending lengthwise of the fly blade of the shearing machine and partly surrounding the same, said guard being movable toward and away from the cloth about two different pivotal axes, one of which is concentric with the fly blade. 120

7. In a cloth shearing machine the combination with a movable cloth rest and coacting shearing couples, a rest lifting and supporting cam for moving said cloth rest to operative relationship with the cutters and maintaining it there, a 125 ratchet wheel connectible with said cam by an intermediate seam controlled connection acting to shift said cam to allow movement of the rest away from such operative position to permit passage of the seam, and means for restoring said 130 cam to normal supporting position after the seam has passed the cloth rest.

8. In a cloth shearing machine the combination with a cloth supporting rest, of a cutter head embracing coacting fly blade and ledger blade, 135 a seam-protecting guard member pivotally mounted on the cutter head in coaxial relation with the fly blade and movable to position between the fly blade and the cloth rest to protect a passing seam, means carried by the cutter head for 140 limiting the movement of said guard to seam-protecting position, means carried by the cloth rest for supporting the guard out of seam-protecting position when the cloth rest and the cutter head are in active relationship, while permitting the free rotation of said guard about its axis to a position above the fly blade to afford 145 full access for the threading of the cloth through the shear.

9. In a shearing machine having coacting 150

shearing cutters combined with a movable cloth rest, a seam controlled mechanism for shifting the rest away from the cutters to allow passage of an approaching seam embracing a continuously rotating ratchet wheel, a rest lifting and supporting cam connection for operatively connecting the ratchet with the cam as the seam approaches the rest to shift the cam to inactive rest position, and self-acting means for restoring the cam to rest lifting and normal supporting position after the seam has passed by the rest.

10. In a cloth shearing machine the combination of a movable cloth rest normally supported in operative relation to shearing cutters, means for raising the cloth rest to, and supporting it in, normal operative position, a continuously rotating actuator, seam controlled means for establishing temporary operative connection between the rest supporting means and the actuator for a predetermined but variable arc of rotation of said actuator to allow movement of the rest from operative position, and means acting when the actuator is disconnected for restoring said rest to normal position.

11. In a cloth shearing machine embracing a movable cloth rest associated with shearing cutters, the combination of a rest supporting cam, yielding means normally acting to move said

cam to rest lifting and normal supporting position, continuously rotating means normally disconnected from said rest supporting means, seam actuated means for establishing temporary connection between said continuously rotating means and said rest supporting means for dropping said rest as the seam approaches, said connection being interrupted after a predetermined but variable arc of rotation to disengage the seam actuated means and allow movement of the rest supporting means to rest lifting position after the seam has travelled a predetermined distance.

12. In a cloth shearing machine the combination with a movable cloth rest and coacting shearing blades, a cam element having supporting engagement with the cloth rest to support the cloth rest in its active raised position and in its inactive depressed position, respectively, and means energized through the medium of a seam travelling toward the shearing elements for shifting said cam from one position to the other to allow the rest to drop to inactive position and permit the passage of the seam, said means acting also, after a predetermined interval, to actuate said cam to raise the cloth rest and support it in active position.
